(57) **CLAIM**

The ornamental design for a stethoscope securing device, as shown and described.

DESCRIPTION

FIG. 1 is a top perspective view of the stethoscope securing device in accordance with the present invention;

FIG. 2 is a side perspective view of the stethoscope securing device of FIG. 1;

FIG. 3 is a right side elevational view of the stethoscope securing device of FIG. 1, the left side elevational view being a mirror image of FIG. 3;

FIG. 4 is a top plan view of the stethoscope securing device of FIG. 1, the bottom plan view being a mirror image of FIG. 4;

FIG. 5 is a front side elevational view of the stethoscope securing device of FIG. 1, the back side elevational view being a mirror image of FIG. 5;

FIG. 6 is a top perspective view of the stethoscope securing device of FIG. 1 in a second reversibly connectable configuration, shown with attached cable ties; and,

FIG. 7 is a right side elevational view of the stethoscope securing device of FIG. 1 shown in use attached to a stethoscope resting around a user's neck.

The broken lines of FIG. 6 showing the attached cable ties and reversibly connectible magnet, ferrous plate, and screw and FIG. 7 showing the attached cable ties, the stethoscope, and user depict environmental subject matter only and form no part of the claimed design.

1 Claim, 4 Drawing Sheets
